UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

CURTAIN ROD.

Application filed September 20, 1924. Serial No. 738,751.

This invention relates to improvements in curtain rods and has reference more particularly to rods adapted for use on bay windows.

5 In some instances rods applied to bay windows have consisted of independent rods and brackets mounted on the several window frames of the bay window, or independent rods with the brackets supporting 10 adjacent ends of adjacent rods, or jointed rods hinged at their adjacent ends. My present invention relates to the latter type of rod, and one object thereof is to provide 15 a jointed rod of such construction that the several sections thereof may be folded flat on each other for convenience in storage and shipment. Another object is to provide an 20 improved friction coupling member for connecting adjacent sections of the complete rod in such a manner that the sections may be easily separated to permit the introduction of an additional section or sections to 25 serve bay windows having four or more window frames, and at the same time the rod sections may be held connected through the coupling members under an expanding friction fit of the former on the coupling members to facilitate mounting and demounting of the rod.

30 Other objects and attendant advantages of the invention will be apparent to persons skilled in the art as the same becomes better understood by reference to the following detailed description taken in connection with 35 the accompanying drawings in which—

Fig. 1 is a horizontal section through a bay window showing my improved curtain rod mounted thereon;

40 Fig. 2 is a front elevation of the structure shown in Fig. 1;

Fig. 3 is a horizontal section, looking downwardly, on the line 3—3 of Fig. 4;

Fig. 4 is a vertical section taken on the line 4—4 of Fig. 3;

45 Figs. 5 and 6 are enlarged transverse sections taken on lines 5—5 and 6—6, respectively, of Fig. 4; and

Fig. 7 is a plan view showing the rod in collapsed or folded position.

50 My improved rod may be made in single, double or triple construction, accordingly as it may be desired to serve, in addition to the regular curtain, side drapes, valances, etc.

55 Referring to the drawing, 10 designates each of the side members and 11 the center

member of an ordinary bay window. 12 designates as a whole the central member and 13 the side members of my improved jointed bay window rod. Since the structural features of all the rods, whether they are employed in single, double or triple mountings, are the same, a description of one will suffice for all. The rods I have herein shown are the well-known hollow "flat" rods, although it is to be understood that the invention is not limited to that or any particular type of rod. To render the rod adaptable to windows of varying widths, the sections 12 and 13 are herein shown as telescopic, in accordance with common practice.

Referring more particularly to Figs. 3, 4, 5 and 6 which best illustrate the structural features of my improved rod coupling member, 14 and 15 designate respectively a pair of relatively short hinge leaves each having the general form of the rod sections which they connect and adapted to telescope within the latter. The proximate ends of these hinge leaves are formed with integral vertical eyes 14' and 15' conveniently made by curling short extensions of the solid wall of the hinge leaf across one end of the latter as clearly shown in Fig. 3. These eyes 14' and 15' embrace a pair of connected hinge pins 75 tles herein shown as the parallel limbs of an oblong loop-shaped hinge member 16. The back wall of each rod as herein shown is split longitudinally, as shown by the slot or groove 17, so that the rear wall of the rod 80 possesses a certain degree of transverse elasticity. To insure the engagement of the hinge leaves 14 and 15 of the coupling within the ends of the rod sections with sufficient 85 force to prevent accidental separation of the rod sections when mounting or taking down the rod or otherwise handling it, and yet permit the coupling members to be withdrawn from the rod sections, I provide for a sliding friction fit, which is ample for the 90 purposes stated and avoids the necessity of positive locking means. This is accomplished, as shown in Figs. 4, 5 and 6 by giving to each hinge leaf 14 and 15 a slight taper both lengthwise and widthwise, as a 95 result of which the outer end of each hinge leaf is readily entered into the end of the rod and, as it is pushed into the latter, expands the metal of the rod slightly both 100 horizontally and vertically, so that the rod 105 110

at its end portion hugs the coupling member with ample friction to prevent easy or accidental displacement, but under a sufficient pull the couplings may be withdrawn from the rods.

For simplicity and economy the hinge leaves 14 and 15 are made of uniform size; and where telescoping rod sections 12 and 13 are employed, in order to give both ends of the intermediate section 12 of the rod the same cross-section as the inner ends of the rods 13, the inner and smaller telescoping member 12' of the rod 12 is at its outer end preferably enlarged to the diameter of the outer rod section, as shown at 12^a, so that the proximate ends of the two rods united by the coupling member are of the same diameter. Manifestly, however, if desired, the parts 12' and 12^a may be formed as separate telescoping rods which would give the same result with a greater number of parts.

While I have herein shown a jointed rod having a single intermediate section, it is manifest that the described construction permits the insertion of two or more jointed sections, if conditions require, in lieu of the single section 12 herein shown.

The jointed rod is supported on the window frame by end brackets 18 and intermediate brackets 19. The end brackets herein shown are identical with those forming the subject-matter of Letters Patent No. 1,563,828, granted to me on the 1st day of December, 1925, and the intermediate brackets are identical with those forming the subject-matter of Letters Patent No. 1,424,337, granted to me on the 1st day of August, 1922. However, the particular supporting bracket is immaterial to my present invention and any other suitable brackets may be used.

It will be observed by reference to the drawings that the parallel limbs of the loop-shaped hinge member 16 are so spaced that the distance between their axes is substantially equal to the thickness of a rod section. Since the axis of each pintle lies in the median vertical plane of the rod section adjacent thereto, the above described structural feature enables the sections of the rod to be folded flat upon each other in the manner indicated in Fig. 7.

I claim—

1. As a new article of manufacture, a flexible curtain rod for bay windows comprising a plurality of hollow flat rod sections, and flexible couplings connecting adjacent ends of adjacent sections, each of said couplings comprising a pair of hinge leaves telescopically engaged within adjacent ends of adjacent sections under a friction fit, and a loop-shaped hinge member formed with parallel limbs forming pintles for said hinge leaves, said loop-shaped member being of a width such that the axes of said hinge pintles are spaced a distance substantially equal to the thickness of a rod section, whereby said rod sections may be folded flat upon each other. 70

2. As a new article of manufacture, a flexible curtain rod for bay windows comprising a plurality of hollow flat rod sections, and flexible couplings connecting adjacent ends of adjacent sections, each of said couplings comprising a pair of longitudinally tapered hinge leaves telescopically engaged with adjacent ends of adjacent rod sections under an expanding friction fit, and a double pintle hinge member connecting adjacent ends of said hinge leaves. 75

3. As a new article of manufacture, a flexible curtain rod for bay windows comprising a plurality of hollow flat rod sections, and flexible couplings connecting adjacent ends of adjacent sections, each of said couplings comprising a pair of transversely tapered hollow hinge leaves telescopically engaged within adjacent ends of adjacent rod sections under an expanding friction fit, and a double pintle hinge member connecting adjacent ends of said hinge leaves. 90

4. As a new article of manufacture, a flexible curtain rod for bay windows comprising a plurality of hollow flat rod sections, and flexible couplings connecting adjacent ends of adjacent sections, each of said couplings comprising a pair of longitudinally and transversely tapered hollow hinge leaves telescopically engaged within adjacent ends of adjacent rod sections under an expanding friction fit, and a double pintle hinge member connecting adjacent ends of said hinge leaves. 100

JAMES H. BOYE.
